UNITED STATES PATENT OFFICE.

PORTER A. WILEY, OF KOKOMO, INDIANA, ASSIGNOR TO KOKOMO ELECTRIC CO., OF KOKOMO, INDIANA, A CORPORATION OF INDIANA.

REVERSIBLE MAGNETO.

1,292,193.

Specification of Letters Patent. Patented Jan. 21, 1919.

Application filed January 19, 1916. Serial No. 72,952.

To all whom it may concern:

Be it known that I, PORTER A. WILEY, a citizen of the United States of America, residing at Kokomo, in the county of Howard and State of Indiana, have invented certain new and useful Improvements in Reversible Magnetos, of which the following is a specification, reference being had therein to the accompanying drawings.

10 In the operation of magnetos in various systems it is frequently desirable to reverse direction of rotation of the same and to do so without any necessity for readjustment of the parts.

15 This invention relates to a reversible magneto and to an arrangement of the parts whereby the generator is as effective in one direction of motion as the other and whereby the change is made without necessity of

20 any alteration of parts, together with means whereby there is no surging or irregular movement of the magneto armature itself.

The invention consists in the matters hereinafter set forth, and more particularly pointed out in the appended claims.

In the drawings,

Figure 1 is a view, partially in side elevation and partially broken away and in section, of a magneto that embodies features of 30 the invention;

Fig. 2 is an end elevation of an interrupter in the position when the device is operating under the direction indicated by the arrow, that is, contra-clockwise;

35 Fig. 3 is a view of the interrupter in advanced position when the magneto is operating in a clockwise direction;

Fig. 4 is a view in detail of a shaft coupling device with the parts in the position shown when the magneto is operating as in 40 Fig. 2;

Fig. 5 is a view in detail of the coupling device showing the parts in the position assumed when the magneto is operating in 45 the direction shown in Fig. 3;

Fig. 6 is a view in sectional detail of the interrupter;

Fig. 7 is a view in detail of an interrupter base;

Fig. 8 is a view in detail of the cam plate 50 of an interrupter, and

Fig. 9 is a view in detail of the shaft coupling parts.

Referring to the drawings a magneto of conventional or standard type with field 55 magnet 1 and armature 2, has a main shaft 3 at one end of which a clutch collar 4 is secured as by a pin 5, feather, key or the like. The collar is counterbored and the resultant flange 6 is cut away for a portion 60 of its length to provide for the reception of a lug 7 that projects from the annular face of a driving sleeve 8. The latter is oscillatory on the shaft 3 and is arranged to be non-rotatably secured to the driving 65 shaft or like part which is used to operate the shaft 3.

On the opposite end, a contact breaker or interrupter is secured in such relation to the adjusted position of the member 6 that 70 it is operative in either direction of rotation of the magneto regardless of whether the stop 7 is at one end of its limit of motion as indicated in Fig. 4, in relation to the collar 4, or at the other limit of motion as 75 indicated in Fig. 5.

Preferably the interrupter consists of a base 9 with annular flange 10 thereon on which the yoke 11 of an interrupter is oscillatory. A suitable stop 12 on the yoke 80 limits the motion of the latter to the arc between two corresponding lugs 13 and 14 or if desirable to reverse the position of the yoke, it may play between other lugs 15 and 16. A cam plate 17 carried by the main 85 shaft 3 to which it is non-rotatably secured in any suitable manner periodically depresses a suitably arranged and designed stud 18 on a spring plate 19 of the yoke so as to separate terminals 20 and 21, one of 90 which is made fast to the yoke and the other to the spring member. The member 21 is insulated from the ground in any suitable manner and it may be conveniently mounted on a binding post 22 or the like. Any 95 other adjustable interrupter mechanism may be used.

A plunger brake 23 on a suitable bushing

or sleeve 24 is pressed by a spring 25 or the like into contact with a brake drum which may be the end collar 26 of the armature. The plunger 23 may be of any suitable material and act as a brake without materially heating or wearing the contacting surfaces. Any other preferred form of brake that is suitable may be used.

The armature of the magneto is of the well known shuttle type as shown diagrammatically in Figs. 4 and 5, and of course the induction therethrough is at a maximum during a certain portion of each revolution, due to the direction and distribution of the lines of force in the magnetic field. For example, with the parts as indicated in Figs. 2 and 4 the magneto running counter-clockwise, the effective range of action of the interrupter is approximately during the arc of movement of the yoke defined by the stops 15 and 16 or the corresponding stops 13 and 14 if the yoke be reversed in direction for convenience of connection in a circuit. Advancing or retarding of the spark if the magneto be in use in an ignition system may be obtained by shifting the yoke through this arc, the position shown in Fig. 2 being that of maximum advance while, when it is at the other end of the limit of its motion, the spark is retarded all in the usual manner. When the direction of the driving shaft of the member which operates the sleeve 8 is reversed, the change in angular relation of the sleeve 8 and the shaft 3 maintains the position of this effective range of action with the only difference that the spark is retarded when the yoke is in the position shown in Fig. 2 and is advanced when in the position shown in Fig. 3.

If for any reason the load on the magneto circuit is varied or the shaft or member which drives the sleeve 8 does not have constant rotation, the momentum of the armature is liable to cause a shift in position of the driving collar 8 in relation to the shaft 3. This is prevented by the constant load which is imposed by the plunger brake so that the armature does not tend to overrun the driving shaft and thereby cause any undesirable change in the position of the driving parts.

As a result of this arrangement the angular position of the effective range of action or induction of the armature is maintained regardless of the direction of rotation of the latter, and without any adjustment by the user, save to advance or retard the sparking movement within this range.

Obviously, changes in the details of construction may be made without departing from the spirit of my invention and I do not care to limit myself to any particular form or arrangement of parts.

What I claim is:—

1. In a magneto, a reversible interrupter 65 therefor adapted to be detached to have the position thereof reversed, for actuation at either side of the magneto to advance or retard the spark within the effective range of the magnetic field, means at the end of the 70 magneto for limiting said adjustment in either position of the interrupter, and means adapted for rotating said interrupter in either direction.

2. In a magneto, an armature shaft, an 75 armature thereon, an interrupter driven by the shaft and adapted for angular adjustment within the effective range of the magnetic field, said adjustment being limited by the end of the magneto at either of opposed 80 points, a collar secured to the shaft, a driving sleeve engaging the collar and having limited angular movement in relation to the collar whereby the angular relation of the two is changed upon reversal of direction 85 of rotation, and means for frictionally retarding the shaft and maintaining the collar and sleeve at either limit of the movement of the latter.

3. In a magneto, an armature shaft, a 90 friction brake constantly imposing a load upon the shaft, a driving collar secured to the shaft, a driving sleeve oscillatory on the shaft in interlocking relation with the collar and having limited angular motion in relation to the latter and a detachable interrupter secured to the shaft in fixed relation to the collar and capable of being reversed for actuation at either side of the magneto to advance or retard the spark. 95

4. In a magneto, an armature shaft, an armature secured thereon, a brake drum secured to the shaft, a brake member yieldingly contacting with the drum, a driven collar secured to the shaft, a driving sleeve 105 oscillatory on the shaft having limited angular movement in relation to the collar with which it interlocks, an interrupter base, and a detachable interrupter yoke on the shaft in fixed relation with the collar, and having a defined oscillatory movement relative to either side of said base. 110

5. In a magneto, a rotatable armature, a detachable interrupter having angular adjustment within a fixed range of the magnetic field, a shaft for the armature operating the interrupter, a fixed collar on the shaft in determined relation to the interrupter, a driving sleeve oscillatory on the shaft having limited angular movement in relation to the collar with which it interlocks, means between said magneto and said interrupter defining the angular adjustment of said interrupter, and means for frictionally imposing a load upon the motor shaft. 115 120 125

6. A magneto comprising field pieces, an

armature shaft, an armature rotated thereby in operative relation to the field, an interrupter having angular adjustment within a fixed range of the magnetic field including 5 a cam member operated by the shaft, a collar secured to the shaft in fixed relation to the interrupter operating member, a sleeve oscillatory on the shaft having limited angular movement in relation to the collar 10 with which it interlocks to drive the shaft,

a friction drum secured to the shaft and a spring plunger brake frictionally engaging the drum.

In testimony whereof I affix my signature in presence of two witnesses.
